UNITED STATES PATENT OFFICE.

CARL AUGUST SCHAEFER, OF HANOVER, GERMANY.

HOLDER FOR ELECTRIC GLOW-LAMPS.

1,120,851.

Specification of Letters Patent. Patented Dec. 15, 1914.

Application filed April 30, 1914. Serial No. 835,506.

To all whom it may concern:

Be it known that I, CARL AUGUST SCHAEFER, a citizen of the German Empire, residing at Hanover, in the German Empire, have 5 invented certain new and useful Improvements in Holders for Electric Glow-Lamps, of which the following is a specification.

The object of this invention is to provide a holder, for electric glow lamps, having 10 means whereby glow lamps of different sizes can be conveniently fixed therein in the most favorable position for giving light.

The invention is illustrated in the accompanying drawing, showing an embodiment 15 thereof, Figures 1 and 2 being two vertical sections, Fig. 1 showing the holder fixed, and Fig. 2 showing same released for purposes of adjustment.

The appliance shown in the drawings 20 comprises a cover or bell *a* inclosing a frame comprising two rods or pillars *b*, a top flange *c*, and a connecting tube or hanger *d*. The rods *b* serve as guides for a bridge *e* to which the lamp holder or socket *f* is fixed. 25 The holder can thus be moved by means of the bridge up and down the guides *b* inside the cover. To enable the bridge to be fixed in any desired position, a rack bar *g* having steps or notches is provided. Said bar has 30 oblique parallel slots *h* above and below the series of steps respectively, these slots being engaged with studs fixed at the top to the flange *c*, and at the bottom to the lamp shade *k*, so that when the bar is moved up or down 35 it also makes a lateral movement. The bridge is provided with a tooth or nose *i* adapted to engage with the steps on the bar *g*. The stepped bar *g* has a tendency to drop by gravity and in doing so to approach 40 the tooth or nose *i* so that the latter becomes engaged with one of the steps. To enable the bridge *e* and holder to be adjusted at a selected height the stepped bar is pushed up, and thus disengaged from the tooth or nose: 45 then the holder is moved to the desired position.

In the drawing the lamp shown in solid lines is a long necked lamp and for holding this lamp the bridge is pushed comparatively high up. For a short necked lamp the bridge is fixed lower down, as indicated by broken lines in Fig. 1, so that in each case the focal point is the same. Fig. 2 shows the adjusting device in its disengaged 55 position; it will be seen that the bridge can now be freely moved.

To enable a lamp to be correctly adjusted the following manipulation is the most practicable: Upward pressure on the stepped bar releases the adjusting device, and the holder is pulled down. The incandescent lamp is then screwed in and gradually pushed up until it is in the most favorable position. The steps being in the form of ratchet teeth the bridge can be pushed up 60 without having to hold the stepped bar in its elevated position. The stepped bar is pushed up by means of a push button *l* working in a hole in the reflector *m*.

For unscrewing the lamp from its socket 70 it is of advantage to let the holder right down, and the lamp can then be held by its neck, immediately below the screw contact, instead of by the bulb. Moreover, when the holder is in its lowest position the connections of the supply wires can be inspected.

In moving the holder the supply wires, which are exposed between the holder and the tube may be liable to foul the rods, and hinder the movement. In order to prevent 80 this, one of the guide rods, preferably the one opposite the stepped bar, may be embraced by an insulating ring through which the wires are threaded, said ring moving with the holder.

What I claim as my invention and desire to secure by Letters Patent of the United States is:—

1. In an appliance for the purpose set forth, the combination of a movable glow 90 lamp holder, means for guiding said holder, a tooth connected to said holder, a movable member alongside said guiding means, having a series of notches adapted to engage said tooth, and guiding means for said 95 toothed member, enabling same to approach and recede from the path of said holder.

2. In an appliance for the purpose set forth the combination of a pillar, a member 100 slidably engaged with said pillar, a lamp socket fixed to said slidably member, a tooth fixed to said slidably member, a movable rack bar parallel with said pillar adapted to engage said tooth, and means obliquely guiding said rack bar, whereby the same 105 recedes from said pillar when performing a lengthwise movement in one direction.

3. In an appliance for the purpose set forth the combination of a movable glow lamp holder, a vertical guide for said holder, 110 a tooth connected to said holder, a movable rack bar parallel with said guide, adapted

to engage said tooth and having oblique slots, and studs engaging said slots, whereby said rack bar is caused to recede from said tooth when moved upward.

- 5 4. In an appliance for the purpose set forth the combination of a movable glow lamp holder, a vertical guide for said holder, a tooth connected to said holder, a movable rack bar parallel with said guide, adapted 10 to engage said tooth and having oblique slots, and studs engaging said slots, whereby said rack bar is caused to recede from said tooth when moved upward, said rack bar having teeth with horizontal upper 15 faces.
5. In an appliance for the purpose set forth the combination of a movable glow

lamp holder, a vertical guide for said holder, a tooth connected to said holder, a movable rack bar parallel with said guide, adapted 20 to engage said tooth and having oblique slots, studs engaging said slots, whereby said rack bar is caused to recede from said tooth when moved upward, a lamp reflector under said holder, and a push mounted in 25 said reflector, engaging the bottom end of said rack bar.

In witness whereof I have signed this specification in the presence of two witnesses.

CARL AUGUST SCHAEFER.
